Patented Aug. 17, 1976

241,006

HANGER BRACKET

Robert S. Wallace, 2881 S. Robertson Blvd.,
Los Angeles, Calif. 90034

Filed Jan. 30, 1975, Ser. No. 545,326

Term of patent 14 years

Int. Cl. D8—08

U.S. Cl. D8—257

FIG.-1

FIG.-2

FIG.-3

FIG.-4

FIG. 1 is a perspective view showing the top, portions of opposite ends and one side of one form of the bracket;

FIG. 2 is a perspective view showing the bottom, portions of opposite ends and the opposite side of the FIG. 1 bracket;

FIG. 3 is a perspective view showing the top, portions of opposite ends and one side of another form of the bracket; and

FIG. 4 is a perspective view showing the bottom, portions of opposite ends and the opposite sides of the FIG. 2 bracket.

I claim:

The ornamental design for a hanger bracket, substantially as shown and described.
